UNITED STATES PATENT OFFICE

2,048,099

TOWEL CABINET

Joseph N. Borroughs, Oakland, Calif.

Application February 23, 1934, Serial No. 712,576

17 Claims. (Cl. 312—37)

This invention is a cabinet provided with means for storing and dispensing towels and similar articles.

One of the objects of the invention is to provide a suitable cabinet with adequate space for storing and dispensing clean towels and for the storage of the soiled towels until they may be conveniently removed for laundering.

A further object is to provide means for maintaining a plurality of towels in a unitary pack assembly, and means for storing and dispensing them in such manner that individual towels are made available for use without permitting complete separation thereof. A further object is to provide means by which a plurality of towels may be retained in a unitary pack assembly by suitable flexible members, and means for so engaging the towels while engaged with the flexible members as to permit the towels to be used in succession and then placed in the storage compartment, without becoming disengaged from said flexible members. A further object is to provide simple and efficient means for supporting a unitary pack assembly of towels in dispensing position and so constructed and arranged as to hold the flexible retaining members in such manner as not to interfere with the dispensing operation. A further object is to provide simple means for maintaining a pack assembly of unused towels in compact feeding relation and to maintain a feeding pressure upon them.

The invention will be hereinafter fully set forth and particularly pointed out in the claims.

In the accompanying drawings:

Figure 1 is a front elevation of a towel dispensing cabinet constructed in accordance with the invention. Figure 2 is a side elevation thereof. Figure 3 is an enlarged front elevation with the doors removed. Figure 4 is a vertical sectional view of Figure 3. Figure 5 is a top plan view with the top member removed, and showing the presser member in operative position. Figure 6 is an enlarged front elevation illustrating the presser member. Fig. 7 is an enlarged view similar to Figure 5. Figure 8 is a transverse sectional view. Figure 9 is a detail perspective view illustrating a portion of one of the towels. Figure 10 is an enlarged perspective view illustrating one of the guide members and its supporting means. Figure 11 is a side elevation partly in section of the members illustrated in Figure 10. Figure 12 is a top plan view and Figure 13 is a side elevation of a modified form of guide member. Figures 14 and 15 are detail front views of the last mentioned

guide members arranged for opposite sides of the cabinet.

Referring to the drawings, C designates a cabinet which may be constructed of any suitable material, the same being constructed of a body 10 having an upper and a lower compartment. The upper compartment is covered by two doors 11 and 12 provided with cut-out portions forming a slot 13 capable of exposing the outermost towel of a pack assembly of clean, unused towels T. The lower compartment is closed by a door 14 hinged at the bottom of the cabinet and provided at its upper end with a transverse cut-away portion 15 which cooperates with similarly arranged cut-away portions 16 of the doors 11, 12 to provide a transverse slot 17 through which may be seen the outermost soiled towel T' of the towel pack unit. The door 14 is yieldably held in closed position by means of spring hinges 18 and the doors 11, 12 are held in closed position by suitable hooks 19. The cabinet C may be supported in any desired manner, but for purposes of illustration is provided with eyelets 20 by means of which it may be suspended from a wall or other support in a well known manner. Rigidly secured to the back wall 25 of the cabinet 10 is a keeper K, preferably in the form of a stirrup-like body 21 provided with diverging arms 22, said body and arms being provided with flanges 23 by which the keeper is secured in position. Two of such keepers are 30 preferably employed with each cabinet, and arranged in spaced relation as clearly shown in Figure 3 of the drawings. Each towel is provided with spaced apart openings O in a well known manner to receive guide members G preferably of U-shape, as shown in Figures 4 and 11. One arm 25 of each guide G is provided with a tapered head 26 complementary to the stirrup 21, the extremity of the other arm 27 of said guide member being free as shown. The towels T of a pack are 40 maintained in permanent inseparable relation by means of endless flexible members such as cords 30 which are passed through the openings O of the towels which have been provided for the reception of the guides G. The cords 30 may be secured in 45 any suitable manner, but as shown in Figures 10 and 11 the extremities of each cord are united by a coupling sleeve 31. By this arrangement, the towels are retained in a unitary assembly at all times not only during dispensing, but also during 50 laundering. In order to permit dispensing of the towels while engaged by the flexible members 30, the arms 25 and 27 of the guide members G are provided with longitudinal grooves 32 of a depth to receive and retain the flexible member from 55

lateral displacement. The head 26 is also provided with an angularly arranged groove 33 communicating with the groove 32 in such manner that the flexible member 30 may also be passed around the 5 end of the head and be clamped between the head 26 and the back wall of the case or cabinet, as shown in Figure 11. This arrangement permits the flexible member 30 to be drawn tightly around its guide G and head 26 and the slack drawn into 10 the space between the arms of the guide member as shown in Figure 11, and the clamping of the flexible member against slippage between the head 26 and the free end of the arm 21, thereby holding the flexible member and the towels carried thereby in such manner that the towels may 15 be freely moved over the guide members G.

Each towel is preferably provided with an opening 35, as shown in detail in Figure 9 and is also provided with a tab 36 preferably of triangular 20 shape. In order to retain the clean, unused towels in vertical position, a supporting device S is provided, the same being formed of a plate-like back 31 having secured thereto a safety pin-like device consisting of a normally stationary member 38 and a movable member 39 connected with the member 38 by a spring portion 40. The member 38 is provided with a hook 41 at its outer end so constructed and arranged as to receive and retain the pointed end of the member 39. The support 25 member is maintained in position by a keeper plate 42 secured to a bar 43 depending from the top of the cabinet C and provided with grooves so arranged as to be slidably engaged by the edges of the plate 37. In practice, the pack assembly 30 of towels is supported in vertical position by first being engaged with the arm 39 of the support member S, which is passed through the openings 35 in the towels, and then engaged with the hook 41. The support member is then slidably inserted 35 in the keeper 42. The two guides G are then inserted through the openings O of the clean towels in such manner that the cords 30 may be brought into the grooves 32, and then said guides are engaged with their respective keepers K, thereby 40 supporting the towels in dispensing position. In this connection, it will be noted that the member S engages the towels near their upper edges and the guides G engage the towels near their lower edges. In order that the towels may be fed forwardly as needed, a presser plate P is provided, the same being slidably mounted upon rods 45 secured in suitable manner within the cabinet. Suitable springs encircling said rods and bearing 45 against the rear end of the case tend to normally urge the presser member P to a forward position. Said presser member is also provided with a slot 47 to provide clearance for the support member S. The presser P may be held in retracted position 50 against the tension of the springs 46 by means of detents 48 shown in the form of resilient members anchored at one end to the side walls of the case with their other ends normally projecting into the path of movement of the presser member. The side walls of the cabinet are provided with 55 recesses 49 to receive the detents 48 so that while they are in retracted position the presser member is free to move forwardly under the tension of its springs.

To charge the cabinet for the purpose of dispensing a pack of towels, the presser member P is moved back until it clears the free ends of the detents 48, whereupon said detents will retain the presser member in retracted position. A unitary pack of towels T held against permanent separa-

tion by two cords 30 is engaged with a support member S in the manner already described. This may be done at the laundry after laundering, or it may be done at the time that the cabinet is charged. In either event, after the support member S is properly engaged with the towels, said support member is inserted into engagement with the guide 42. Each series of holes O is then engaged with a guide member G in the manner already described, and said guide members are engaged with their keepers in such manner as to take up the slack of the cords 30 and to prevent loosening thereof during the dispensing operation. The free end of the member 39 is then disengaged from the hook 41 and the towels are thereby released to be fed forwardly, their upper ends being supported by the arm 39 and their lower ends being guided and held in spread relation by means of the guides G. By then pressing the detents 48 into their recesses 49, the presser member P is released but the same is held by the operator in such manner as to prevent maximum forward movement thereof until the doors 11 and 12 have been closed and secured in locked position. It will be noted that the tab 36 of the foremost towel T is then projecting through the slot 13. When it is desired to use a towel, the tab 36 of the outermost towel is grasped and the towel is pulled forwardly through the slot 13 and out of engagement with the support member S and it will slide forwardly on the arms 25 of the guide members G until it may be drawn through the slot 17, into which the outer portions of said guides project. After the towel has been used, the door 14 may be moved back upon its hinges 18 and the used towel allowed to drop into the lower compartment of the cabinet and upon release of said door 14 the towel is moved back upon the arms 27 of the guide members G, thereby presenting the next towel for use.

In Figures 12 to 15 both inclusive, the guide members G' are formed of two members 25^a and 27^a connected by a U-shaped portion, the member 25^a being rotatably mounted in the head 26^a as shown. Said head is preferably in the form of a metal stamping provided with flanges 50 arranged in downwardly converging relation and constructed and arranged to engage a correspondingly shaped keeper 50^a (Figure 3) secured to the wall of the cabinet. Each head 26^a is provided with a slot 33^a to accommodate the flexible member 30^a, and each is provided at its lower end with a lateral slot 51 to receive the free end of the member 27^a of a guide member G'. In this form the slack of the flexible member 30^a is doubled upon itself to form a loop and caught in a hook 52 as clearly shown in Figure 13.

The advantages of the invention will be readily understood by those skilled in the art to which it belongs. For instance, it will be observed that the towels are assembled into a unitary pack which is maintained by the flexible cords as long as the towels themselves are intact both while laundering and while being dispensed. A further advantage is that simple means have been provided by means of which the dispensing of the towels is accomplished without requiring a disconnection of the flexible member, and while said flexible member is still intact. A further advantage is that the towels are maintained in a convenient form for dispensing and that they may be successively used as occasion may require and the used towels stored in a proper chamber, 75

while still engaged by the guiding means and by the flexible retaining means.

Having thus explained the nature of the invention and described an operative manner of 5 constructing and using the same, although without attempting to set forth all of the forms in which it may be made, or all of the forms of its use, what is claimed is:—

1. In a towel dispensing device, the combination 10 with a plurality of towels, of a flexible member having its ends permanently connected in such manner as to movably hold all of said towels in a unitary pack assembly, a cabinet, a keeper supported by said cabinet, a guiding member provided with a head complementary to said keeper 15 and removably engaging the same, and means for presenting said towels to dispensing position while in engagement with said guiding member and said flexible member, said head having means co-operating with said keeper to grip said flexible member.

2. In a towel dispensing device, the combination 25 with a plurality of towels, of a flexible member having its ends permanently connected in such manner as to movably hold all of said towels in a unitary pack assembly, a cabinet, a keeper supported by said cabinet, a U-shaped guide member having a head complementary to said keeper and removably engaging the same, and means for presenting 30 said towels to dispensing position while in engagement with said guide means and said flexible member, said guide member and said head being grooved to receive said flexible member.

3. In a towel dispensing device comprising a 35 cabinet having a chamber therein, the combination of a plurality of towels adapted to be disposed in superposed relationship in said chamber, a flexible member formed in a closed loop movably contacting each of said towels, a rigid guide member contacting each of said towels and having a portion thereof disposed within said towel chamber, and means for securing said flexible member and said guide member together with the portion of said flexible member contacting said 45 towels lying subjacent the periphery of said guide member.

4. In a towel dispensing device comprising a cabinet having a chamber therein, the combination 50 of a plurality of towels adapted to be disposed in superposed relationship in said chamber, a flexible member formed in a closed loop movably contacting each of said towels, a rigid guide member contacting each of said towels and having a portion thereof disposed within said towel chamber, and means for securing said flexible member and said guide member together in parallel 55 relationship with the portion of said flexible member contacting said towels lying subjacent the periphery of said guide member.

5. In a towel dispensing device comprising a cabinet having a dispensing aperture therein opening into a towel chamber, the combination of a plurality of separable towels formed in a unitary pack, a flexible member formed in a closed loop 60 movably contacting each of said towels, a U-shaped guide member having a portion thereof projecting through said aperture and contacting said towels for mounting said pack in said chamber adjacent said dispensing aperture, means for securing said flexible member to said guide member subjacent the periphery thereof, and means 65 operable after removal of a towel through said dispensing aperture for moving the next succeeding towel into position adjacent said aperture.

6. In a towel dispensing device comprising a cabinet having a dispensing aperture therein opening into a towel chamber, the combination of a plurality of separable towels formed in a unitary pack, a flexible member formed in a closed loop 5 movably contacting each of said towels, a U-shaped guide member having a portion thereof projecting through said aperture and contacting said towels for mounting said pack in said chamber adjacent said dispensing aperture, means for removably securing said flexible member to said guide member subjacent the periphery thereof, and means operable after removal of a towel through said dispensing aperture for moving the next succeeding 15 towel into position adjacent said aperture.

7. In a towel dispensing device comprising a cabinet having a dispensing aperture therein opening into a towel chamber, the combination of a plurality of separable towels formed in a unitary pack, a flexible member formed in a closed loop 20 movably engaging each of said towels, a U-shaped guide member engaging said towels having a portion thereof projecting through said aperture and provided with a longitudinal groove 25 in the surface thereof, means for securing said flexible member to said guide means positioned in said longitudinal groove, and means operable after removal of a towel through said dispensing aperture for moving the next succeeding towel into 30 position adjacent said aperture.

8. In a towel dispensing device comprising a cabinet having a dispensing aperture therein opening into a towel chamber, the combination of a plurality of separable towels formed in a unitary pack, a flexible member formed in a closed loop 35 movably engaging each of said towels, a U-shaped guide member engaging said towels having a portion thereof projecting through said aperture and provided with a longitudinal groove 40 in the surface thereof, means for frictionally securing said flexible member to said guide means positioned in said longitudinal groove, and means operable after removal of a towel through said dispensing aperture for moving the next succeeding 45 towel into position adjacent said aperture.

9. In a towel dispensing device comprising a cabinet having a dispensing aperture therein opening into a towel chamber, the combination of a plurality of separable towels formed in a unitary pack, a flexible member formed in a closed loop 50 movably engaging each of said towels, a U-shaped member engaging all of said towels for supporting said pack in said chamber adjacent said dispensing aperture, and means on said U-shaped member for engaging and rigidly holding said flexible member in U-shaped formation.

10. In a towel dispensing device comprising a cabinet having a dispensing aperture therein opening into a towel chamber, the combination of a plurality of separable towels formed in a unitary pack, a flexible member formed in a closed loop 60 movably engaging each of said towels, a U-shaped member engaging all of said towels for supporting said pack in said chamber adjacent said dispensing 65 aperture, means on said U-shaped member for engaging and rigidly holding said flexible member in U-shaped formation, and means for removably mounting said U-shaped member in said chamber.

11. In a towel dispensing device comprising a cabinet having a dispensing aperture therein opening into a towel chamber, the combination of a plurality of separable towels formed in a unitary pack, a flexible member formed in a closed 70

75

loop movably engaging each of said towels, a U-shaped member engaging all of said towels for supporting said pack in said chamber adjacent said dispensing aperture, means on said U-shaped member for engaging and rigidly holding said flexible member in U-shaped formation, means for removably mounting said U-shaped member in said chamber, and means operable after removal of a towel through said dispensing aperture for moving the next succeeding towel of the pack into position adjacent said aperture.

12. In a towel dispensing device comprising a cabinet having a dispensing aperture therein opening into a chamber, the combination of a plurality of towels each having an aperture formed therein and assembled into a unitary pack with all of said apertures in alinement, a flexible member formed in a closed loop and passing through all of said apertures, a rigid member 20 passing through said apertures and having a longitudinal groove therein, means for securing said flexible member in said groove in rigid formation, and means for mounting said rigid member in said chamber to support said pack adjacent 25 said dispensing aperture.

13. In a towel dispensing device comprising a cabinet having a dispensing aperture therein opening into a chamber, the combination of a plurality of towels each having an aperture 30 formed therein and assembled into a unitary pack with all of said apertures in alinement, a flexible member formed in a closed loop and passing through all of said apertures, a rigid member passing through said apertures and having a 35 longitudinal groove therein, means for securing said flexible member in said groove in rigid formation, means for mounting said rigid member in said chamber to support said pack adjacent said dispensing aperture, and means operable 40 after removal of a towel from said chamber through said dispensing aperture for moving the next succeeding towel in the pack into position adjacent said aperture.

14. In a towel dispensing device comprising a 45 cabinet having a plurality of chambers therein, the combination of a plurality of separable towels assembled into a unitary pack, an endless flexible member engaging each of said towels, a rigid U-shaped guide member engaging said towels and 50 having portions thereof disposed in each of said

chambers for guiding said towels from one of said chambers to the other, and means for removably securing a portion of said flexible member to said guide means subjacent the periphery thereof.

15. In a towel dispensing device comprising a cabinet having a plurality of chambers therein, the combination of a plurality of separable towels assembled into a unitary pack, an endless flexible member movably engaging each of said towels, a 10 guide member movably engaging said towels for guiding said towels from one of said chambers to the other, said guide means comprising a rigid U-shaped bar having parallel portions each entering a chamber, means for removably mounting 15 said guide means in one of said chambers, and means for removably securing a portion of said flexible member to said guide means subjacent the periphery thereof.

16. In a towel dispensing device comprising a 20 cabinet having a plurality of chambers therein, the combination of a plurality of separable towels assembled into a unitary pack, an endless flexible member movably engaging each of said towels, a guide member movably engaging said towels for 25 guiding said towels from one of said chambers to the other, said guide means comprising a rigid U-shaped bar having parallel portions each entering a chamber and a longitudinal groove in the surface thereof, means for removably mounting 30 said guide means in one of said chambers, and means for removably securing said flexible member to said guide means in said longitudinal groove.

17. In a towel dispensing device comprising a 35 cabinet having a plurality of chambers therein, the combination of a plurality of separable towels assembled into a unitary pack, an endless flexible cord movably engaging each of said towels, a guide member movably engaging said towels for 40 guiding said towels from one of said chambers to the other, said guide means comprising a rigid U-shaped bar having parallel portions thereof each entering a chamber and a longitudinal 45 groove on the surface thereof, means for removably mounting said guide means in one of said chambers, and means for removably securing said cord to said guide means in said longitudinal groove.

JOSEPH N. BORROUGHS. 50
